chinery Company, Piqua, Ohio

Application March 21, 1950, Serial No. 151,012

14 Claims. (Cl. 23—310)

1 This invention relates to solvent extraction and more particularly to solvent extraction in which the solids to be treated are carried in open top, perforated bottom, drainage baskets in an elongated, endless path during which a solvent-containing liquid is passed repeatedly through the solids in the baskets. Heretofore in basket type extractors, the baskets were commonly carried in a vertically elongated path and the apparatus, if of substantial capacity, necessarily was rather tall, usually occupying more than one floor. Tall apparatus must be built quite rigid and, therefore, the cost of the apparatus has been relatively high. Special buildings were sometimes necessary to accommodate the tall apparatus.

An object of this invention is to provide an improved method and apparatus for solvent extraction which will overcome the objections against prior methods and apparatus for basket type solvent extraction, which will utilize a relatively low cost installation, which may be operated as a one floor system, with which the extraction apparatus or equipment may be pre-assembled at the factory, and unloaded and placed on the customer's previously prepared concrete foundation, and which may utilize relatively cheap prefabricated buildings for housing the equipment.

Another object of the invention is to provide an improved and efficient method and apparatus for solvent extraction, which will require a minimum of supervisory attention, which may be made largely automatic and continuous in operation, and which is inexpensive.

Another object of the invention is to provide an improved solvent extraction apparatus of the basket type, which will be efficient in operation, which will have its various parts easily accessible for servicing, which will be relatively low in height, which enables one to obtain the benefits of continuous miscella filtration in the baskets without interference with the extraction, in which the effectiveness of the extraction will be a maximum, and which will be relatively compact, simple, efficient, trouble-free and inexpensive.

Other objects and advantages will be apparent from the following description of one embodiment of the invention, and the novel features will be particularly pointed out hereinafter in connection with the appended claims.

In the accompanying drawing:

Fig. 1 is a side elevation, on a reduced scale, of apparatus constructed in accordance with this invention;

2 Fig. 2 is a longitudinal, sectional elevation on a somewhat larger scale, of one end portion of the apparatus shown in Fig. 1;

Fig. 3 is a longitudinal, sectional elevation through the opposite end of the apparatus;

Fig. 4 is a plan of some of the hydraulic controls, and

Fig. 5 is a transverse, sectional elevation through the charging and unloading end of the apparatus shown in Figs. 1 to 3, the section being taken approximately along the line 5—5, Fig. 2.

In the illustrated embodiment of the invention, the apparatus includes a housing 1 which is horizontally elongated and suitably mounted on base pedestals 2. This housing 1 may be, and usually is formed of a structural steel frame with sheet metal panels attached to the frame and forming the enclosing walls of the same. Supported by the frame within the housing, at opposite ends thereof, are shafts 3 and 4 which are rotatably mounted in the housing frame. Fixed on the shaft 3 are a pair of sprocket wheels 5, spaced apart along and concentric with the same. Similarly, a pair of sprocket wheels 6 are concentric with, spaced apart along and fixed to the shaft 4.

A pair of sprocket chains 7, one at each side of the housing, extend between the run over the sprocket wheels 5 and 6 at each side of the housing. The sprocket wheels and the chains form an endless, closed loop carrier which is horizontally elongated. The bearings 4a for the ends of shaft 4 are adjustable lengthwise of the housing to loosen or tighten the endless loop carrier. The shaft 3 carries a sprocket 8, Fig. 1, which is driven by a chain 9 from a chain 10, fixed upon the shaft 11 of a gear reducer of an electric motor 12. The motor thus serves to drive the shaft 3 at a slow, continuous rate and thus cause endless loop travel of the chains.

The motor 12 is mounted in a frame 13, and mounted on this frame 13 is a suitable hydraulic control mechanism 14 (see Fig. 4), having a rotatable cam shaft 15 carrying a sprocket 16. The motor shaft 11 also carries a chain which operates an endless belt 17 that runs over the sprocket 16 on the cam shaft 15. Fixed on the shaft 15 are a plurality of cams 18, the peripheries of which operate valve stems 20 of the valves 21 in a desired, timed sequence and for desired durations. These valves 21, when operated, pass an operating fluid, such as compressed air or an operating liquid, to operate hydraulic motors that operate certain controls of the apparatus, as will be explained later herein.

A plurality of drainage baskets 22 are arranged in succession along and between the sprocket chains 7, and supported between corresponding parts of the chains, as shown in Figs. 1, 2 and 3. Each basket is provided at each end with a supporting stud 23, the studs at opposite ends of each basket being axially aligned and pivotally supporting the basket from the chains. Each basket is thus individually and rockably supported by the chains that form the endless carrier, and are free to pivot upon horizontal axes as they travel with the chains in a horizontally elongated, endless loop path. Each chain carriers rollers 24, Fig. 5, arranged at intervals along its length, which roll upon shelves 25 provided on the inside walls of the frame of the housing so as to support the chains against sagging in both upper and lower stretches while passing between the sprocket wheels 5 and 6.

Each chain also carries pins 26 midway between the studs 23, and pins 26 and rollers 24 are received in the notches 27 in the sprocket wheels 5 and 6 to provide a driving connection between them. Each end of each basket is also provided with three projecting pins 27a arranged in an equitriangular spacing about the adjacent stud 23. When the baskets are upright, two of the pins 27a will be equal distances above a horizontal plane through the axes of studs 23, horizontally aligned and disposed at equal distances from a vertical plane through the axis of studs 23. The third pin 27a will be aligned vertically with the adjacent stud 23. The inside face of the frame of the housing 1 is also provided with ledges or shelves 28 which extend horizontally, adjacent the upper and lower stretches of the carrier, and provide tracks on which ride the horizontally aligned pins 27a of each basket end. The engagement of the horizontally aligned pins 27 with the shelves 28 prevents lateral tilting of the baskets during their horizontal travel. Suitable means is also provided at the sprockets 6 to keep the baskets upright while descending from the upper stretch of the carrier to the lower stretch, as shown at the right hand end of Fig. 3.

Various ways have been devised for keeping baskets upright while descending at the sprocket wheels 6, and while any of them may be used, this is accomplished in the illustrated apparatus by supporting on the shaft 4, a pair of additional sprocket wheels 29 spaced apart along the shaft 4, with a sprocket wheel 29 adjacent each wheel 6. Each sprocket wheel 29 is somewhat smaller than the sprocket wheel 6 and it is provided in its periphery with notches 30, as shown in Fig. 3. The wheels 29 are driven by suitable gearing at about $\frac{5}{6}$ the speed of sprockets 6. As each basket approaches the right hand end of the carrier, see Fig. 3, the lower pins 27a on the basket will move into peripherally spaced notches 30 of sprocket wheels 29, and when each basket is immediately above the shaft 4, the lower pin 27a of that basket will be in the center of a notch 30, as shown in Fig. 3.

During continued rotation of the shaft 4 and the sprocket wheels 6 and 29, the lower pin 27a at each end of the basket will be cammed to the right in Fig. 3, so as to gradually right out of a notch 30, which causes a partial rotation of the basket on the axes of the studs 23, and during this movement the second of the two upper pins 27a on that end of that basket will slowly enter notches 30 which follow those in which the lower pins 27a were engaged. As the rotation continues, the notches 30 will slowly rotate the

basket through engagement with the pins 27a to keep the baskets upright, and as they move away from the sprockets 6 and 29 (see Fig. 3), the two upper, horizontally aligned pins will again hold the baskets against rocking.

As the baskets in the lower stretch of the carrier approach the sprocket wheels 5, as shown at the left in Fig. 2, the shelves 25 will end before the baskets reach the sprocket wheels 5, in order that the baskets may be rotated about the axes of their studs 23 to invert them and empty their contents into a discharge hopper 32. Any suitable means may be employed for inverting the baskets over the hopper 32, but as shown, there is provided at each side of the housing a hump-like cam member 33 having a cam surface 34 which is disposed in the path of travel of the lower pin 27a of the basket at that side of the housing. As shown in Fig. 2, as the upper or horizontally aligned pins 27a on the ends of each basket leave the shelves 28 in the lower stretch, Each upper leading pin 27a on each basket will leave its related shelf 28 shortly before the lower pins 27a engage the cam surfaces 34 and, therefore, the leading pins 27a will pass above the humps of the cam surfaces 34 as the lower pins 27a are cammed backwardly and upwardly (counterclockwise in Fig. 2) by the surfaces 34. This causes that basket to move into a half inverted position, shown in Fig. 2, in which the leading pins 27a have moved down the trailing sides of the humps of the cam members 33 before the lower pins 27 reach the crests of the cam surfaces 34.

As that basket continues to travel bodily to the left in Fig. 2, the leading horizontal pins 27a which have reached approximately the bottoms of the cam surfaces 34, will engage with upstanding but inclined cam surfaces 35 that retard those pins 27a, so that continued movement of the basket will complete its inversion over the hopper 32. This places the second of the horizontally aligned pins at each end of that basket uppermost, with the other pins 27a at that end of the basket horizontally aligned but below the chain. As that basket moved into this position, the single upper pin 27a at each end of that basket will move into notches or recesses 36 in the ends of radial arms 37 forming parts of spaced wheels 38 which are fixed on the shaft 3.

There is also a wheel 38 at each side of the housing. Each notch 36 is arcuately concave, and as a pin 27 moves into the notch, the basket is held against further rotation about the axis 55 of its supporting studs 23. These inverted baskets will then be held against rotation on the axes of their studs 23 as they travel upwardly or ascend to the upper stretch of their travel. The travel of the baskets through a half-revolution with the sprocket wheel 5 will again place them upright as they enter upon the upper horizontal stretch of their travel. As the baskets reach the upper end of their ascent at the left hand end as in Fig. 2, the pair of pins 27a which are then uppermost will then move over the shelves 28 which keeps the baskets from tilting during their travel to the right hand end of the housing in Figs. 2 and 3.

A charging hopper 39, Figs. 1 and 2, is disposed above the baskets at the beginning of their travel in the upper stretch, so that when each basket is below the hopper 39, a measured charge of solids to be treated may be deposited in that basket. This charging operation is repeated each time a basket passes beneath the hopper

39. Any suitable charging means may be employed, but that illustrated is identified as a double clam shell, gate unit which has a pair of upper swinging gate elements 40 (shown by dash lines in Fig. 1), pivoted on shafts 41, so as to swing either downwardly, as shown in dash lines in Fig. 1, or toward each other until they engage and stop the flow of solids in the conduit 42. Similar plates 43 are pivoted on shafts 44, as shown by dash lines in Fig. 1, so as to swing together to stop flow of solids that have passed the swinging gates 40, or open and pass solids. The shafts 41 are provided with operating arms 45 and 46 which are pivotally connected by link 47, so that when the lever or arm 46 is rocked, the plates 43 will swing toward each other or apart depending upon the direction in which the arm 46 is rocked.

The arm 46 is pivotally connected by pin 48 and a slot to a piston 49 of a hydraulic motor 50 of the double acting type, and which is controlled by pipes 51 and 52 that admit operating fluid to opposite ends of the motor 50. The fluid is vented from one end while fluid under pressure is admitted to the opposite end, as is usual in double acting, reciprocating hydraulic motors. The motor 50 is pivoted to the frame to enable the pin 48 to move with the arm 46 as it moves in a slight arcuate path as it rocks. Arms 53 and 54 are fixed on the shafts 44 for the lower gates, and these arms are pivotally connected by a link 55, so that when the arm 54 is rocked, the gates 43 will swing toward or from each other, depending upon the direction of rocking of the arm 54.

A hydraulic motor 55a is pivotally mounted and provided with a reciprocating piston 56 that is pivotally connected by a pin 57 to the arm 54, so that reciprocation of piston 56 will rock the arm 54 and cause the gate plates 43 to swing toward and from each other. The motor 55 is supplied with operating fluid alternately through pipes 58 and 59. The pipes 51, 52, 58 and 59 lead to the valves 21, shown in Fig. 4, so that at the proper intervals in the cycle of operation, the valves 21 will admit operating fluid alternately to the opposite ends of the motors 50 and 55, and thus operate the gates 40 and 43 in the proper sequence to measure uniform charges of the solids to be treated and deposit them in succession in the baskets as they move one after another into proper position beneath the hopper 39.

Disposed above the baskets as they travel horizontally in the upper stretch are a plurality of distributing pans 60, 61, 62, 63, 64 and 65 arranged end to end in succession. Another series of similar distributing pans 66, 67 and 68 are arranged in end to end succession above the baskets in the initial part of the lower stretch of their horizontal travel as shown in Fig. 1. Each of these distributing pans 60-68 inclusive, is provided with a bottom 69, see Fig. 5, which undulates from side to side so as to provide a plurality of shallow troughs or grooves 70 that run or extend parallel to the direction of travel of the baskets. These grooves 70 are arranged side by side in a direction from side to side of the housing, and the bottom of each groove is provided with apertures spaced apart lengthwise of the groove. Thus, when liquid is placed in each of these pans, it will be discharged as a plurality of small streams distributed approximately uniformly over the entire bottom area of the pan, so as to produce the effect of a con-

tinuous rain of liquid over the baskets as they travel beneath the pans. The capacity of each pan and of the apertures in the bottom thereof is sufficient to keep the baskets flooded and supply the liquid faster than it can drain out, for a purpose which will appear herein later.

A pair of spray pipes 71 (Fig. 2), arranged inside the bottom part of the hopper 39, extend crosswise of the direction of travel of baskets beneath the hopper. These pipes 71 have a plurality of downwardly opening apertures along their lengths that discharge streams of liquid downwardly from the bottom of the charging hopper 39 into any basket beneath it. These pipes 71 are individually controlled by valves 72, Fig. 1, and connected to a common supply pipe 73.

Disposed below the baskets during their horizontal travel in the upper stretch are a row of collecting pans 74, 75 and 76 abutting end to end, and similarly arranged below the baskets in their horizontal travel in the lower stretch and below the descending baskets are similar collecting pans 77, 78 and 79, also disposed end to end. The pan 79 extends to the discharge or unloading hopper 32. Each collecting pan 74 to 79 inclusive, has a depressed bottom so as to drain any liquid falling therein to an outlet pipe. A pipe 80 drains liquid from the bottom of the pan 74, a pipe 81 drains liquid from the bottom of pan 75, a pipe 82 drains liquid from the bottom of pan 76 and a pipe 83 drains liquid from the bottom of pan 77, a pipe 84 drains liquid from the bottom of pan 78 and a pipe 85 drains liquid from the bottom of pan 79.

The pipe 80, which receives liquid from the bottom of the first collecting pan 74 leads to the intake side of a motor operated pump 86. At its output side the pump 86 is connected to a vertically extending pipe 87 which is provided at its top with branches 88 and 89, the branch 88 discharging into the distributing pan 60 and the branch 89 discharging into the distributing pan 61. Branch 88 is controlled by a valve 90 and branch 89 is controlled by a valve 91. The pipe 81 which drains liquid from the second collecting pan 75 is connected to the intake side of a motor driven pump 82, and the output side of that pump is connected to a pipe 93 which extends to the top of the housing and is there provided with branches 94 and 95. The branch 94, controlled by a valve 96, discharges into the distributing pan 62, and the branch 95, which is controlled by a valve 97, discharges into the distributing pan 63. The pipe 82, which drains liquid from the collecting pan 76, is connected to the intake side of a motor driven pump 98, and a pipe 99, which is connected to the output side of a motor driven pump 98 contains a valve 99a in series therein and discharges into the distributing pan 64.

The pipe 83 which drains liquid from the first of the lower collecting pans 77 is connected to the intake side of a motor driven pump 100, to the output side of which is connected a pipe 101 that contains a branch 102 controlled by a valve 103 which discharges into the distributing pan 65. Another branch 104 is connected to the pipe 73 that supplies the spray pipes 71. The branch 104 is provided with a controlling valve 105 which is operated by a hydraulic motor 106. A pipe 107 leads from motor 106 to one of the valves 21, shown in Fig. 4. The branch 104 also, before it reaches the valve 105, is provided with another branch 108 which leads to a filter (not shown) provided on the top of the housing, in which any suspended solids in the liquid delivered by the

branch 108 may be filtered out. The liquid passing through the filter is then treated to recover the solvent and separate it from the extracted material, as usual in the solvent extraction process, but which is not illustrated and described herein, since it forms no part of the present invention.

The pipe 84 which drains liquid from the bottom of the collecting pan 78 is connected to the intake side of a motor operated pump 109. A pipe 110, which is connected to the output side of pump 109 discharges liquid into the distributing pan 67, and through a branch 111 also into the distributing pan 66. The pipe 85 which drains liquid from the pan 79 is connected to the intake side of the motor operated pump 112, and a pipe 113, which is connected to the output side of the pump 112, discharges the liquid into the distributing pan 68.

Fresh solvent from a suitable storage tank is conducted first through a heater, not shown, where it is heated and then delivered by a pipe 114, controlled by a valve 115, to two branch pipes 116 and 117. Valve 115 is operated by a hydraulic motor 118 which, in turn, is operated by a fluid under pressure supplied by a pipe 119 from one of the valves 21 of Fig. 4. Pipe 116 has a regulating valve 120 and pipe 117 has a regulating valve 121. The pipe 116 extends horizontally across the top of the basket 22 just before it reaches the inverting mechanism, Fig. 2, and has a plurality of downwardly opening apertures arranged in a row along its length in the portion above the baskets, so as to discharge a spray of liquid downwardly into any basket beneath it. Similarly, the pipe 117 extends horizontally across the interior of the housing and above the baskets passing beneath it just before they pass beneath the spray pipe 116.

The operation of the illustrated apparatus will now be described.

With the motor 12 operating, the shaft 3 will be positively and continuously rotated at a slow rate, preferably one which will move the baskets from about one to three feet per minute. This rate of travel is such that one basket cycle is completed in from about one to two minutes. The solids to be treated are supplied continuously through the conduit 42 to the charging hopper 39, and the hydraulic motors 50 and 55a are operated by the valve mechanism of Fig. 4 in timed relation to each other and to the travel of the baskets, so as to discharge a measured charge of solids into each basket below the hopper 39. The valve 105 is operated by one of the cam controlled valves 21 of the master control mechanism shown in Fig. 4, so that just slightly prior to the operation of the gate plates 43, the valve 105 will be opened to deliver solvent-containing liquid from the pump 100 to the pipes 71 into the basket, and this discharge continues while the basket is being filled and for a short interval after it is filled.

The discharge of liquid into the basket beneath hopper 39 through pipes 71 is faster than the liquid can drain out of that basket through its perforated bottom, with the result that a considerable amount of free liquid will be retained within the basket before the charge begins to enter. The solids are therefore discharged into a body of liquid in the basket, with the flow continuing during charging, and while the solids are heavier than the liquid displaced thereby, they will be buoyed up by the liquid to such an extent that they will not settle and pack tightly in the bottom of the basket. Packing of the solids would reduce the flow of liquid through

the mass. The liquid draining from this basket will be collected in the pan 74. After the basket has been filled and has largely moved out of charge receiving position, the valve 105 closes until another basket has moved approximately into charge-receiving position beneath the hopper 39. The valve 106 is then again opened to place a pool of liquid in the basket into which another charge of solids to be treated is delivered. This cycle of operation is repeated as each basket comes beneath the hopper 39.

As the baskets move under the pan 60, which is very shortly after they leave a position beneath the hopper 39, they will receive a rain of further solvent-containing liquid that will continue throughout their travel beneath the pans 60-65 successively. The rate of fall of the liquid in this rain is faster than the liquid can drain from the bottoms of the loaded baskets, and this will keep the loaded baskets flooded with the liquid so that the solids in each basket will be buoyed up enough to prevent packing tightly. This permits maximum flow of the liquid through the mass of solids in each basket, and the flow of liquid through the contents of the baskets will be fairly uniform across the entire top face area of this basket, thus increasing the efficiency of the extraction. Some of the rain will fall between the baskets, but all will be collected in the collecting pans beneath the baskets in their travel.

It will be noted that the liquid from the pan 74 will be delivered partly to the pan 63 and partly to the pan 64 so that some of the liquid passing between the distributing pan 60 and the collecting pan 74 will be advanced to the pan 64 and drain into the next collecting pan 75. The liquid collected in the pan 75 will be delivered partly to pan 62, which will drain into pan 75, and partly into the next pan 63 from which it drains into the next pan 76. Thus the solvent-containing liquid will gradually progress from distributing pan to distributing pan throughout the entire upper stretch of the travel of the baskets until the pan 64 is reached. The pan 66, which is over the descending baskets, receives its supply of solvent-containing liquid from the pan 77 into which it again drains. The fresh, solvent-containing liquid in heated condition is sprayed into the baskets while in two positions just before they reach the inverting positions under the control of the valve 115. Valve 115 is controlled from one of the valves 21 in timed relation to the travel of the baskets.

This fresh solvent is delivered intermittently so that a charge is given into each basket only while the basket is immediately below the pipes 116 or 117. This prevents waste of the fresh, solvent-containing liquid. This fresh, solvent-containing liquid, after passing through the baskets, which are in the positions just before the baskets are emptied, drains into the pan 79 where it is collected and forwarded to the last distributing pan 68. The liquid from pan 68 falls as rain on the baskets passing beneath it, and substantially all of it will be collected in the pan 78. From pan 78 the liquid will be delivered to the pans 66 and 67. Thus, the solvent-containing liquid will gradually progress along the housing from basket to basket concurrently with the travel of the baskets in the upper stretch but in a countercurrent direction relatively to the travel of the baskets in the lower stretch.

The fresh solvent which is added to the baskets just before the baskets are inverted and

washes off from the solids substantially all of the solvent-containing liquid which carries in solution the component parts that were to be extracted so that the solids at the time they are emptied into the hopper 32 will be wet with only substantially pure solvent, and with very little or no solvent which carries therein any of the component to be extracted. The concurrent travel or progress of the baskets and solvent will thus occur for more than one third of the travel of baskets between loading and unloading positions, and the counter progression of the baskets and solvent will also then continue for at least about one-third of the travel of the baskets between loading and unloading positions.

The solvent-containing liquid which collects in pan 17 will contain the largest amount or concentration of dissolved component from the solids, and part of this is discharged into the baskets at the time of filling and part of it passed to the filter where solids suspended in the liquid are removed, and then the dissolved component is separated from the solvent. The amount of miscella or solvent-containing liquid removed through the filter will, of course, vary directly with the amount of the fresh solvent which is delivered through the pipe 114. It will be noted that the liquid is repeatedly passed through the baskets so that the solids in each basket function as step by step filters and remove substantially all fine solids that may be carried in suspension in the solvent-containing liquid or miscella.

The progression of the solvent-containing liquid or miscella along the upper stretch of the exterior is concurrent with the travel of the baskets, and during this concurrent travel the highest concentrated miscella and solids with the highest concentration of the oil therein are in moving contact with each other and travel along together. We have found by experience that the strength of the miscella or the amount of extracted oil contained in the solvent of the miscella has no appreciable effect upon the extracting power of the solvent up to concentrations of oil as high as 35% to 40%. As a result, the concurrent cycle thus provided has maximum effectiveness for extraction, and in addition, we are able to filter this miscella through the solids of the baskets before the miscella is pumped to the final filter. This filter on top of the housing is really only a safety filter, because substantially all filtering of the miscella is done in the baskets during the extraction.

Attention is called to the fact that just as the solids are dropped into the basket through a hopper 39, a substantial amount of miscella is deposited in the basket so as to provide a substantial body of liquid in the basket which builds up since it is supplied faster than it can drain out. When the solids from the hopper 39 fall into this body of miscella already in the basket, they will be buoyed up by the liquid miscella so that they will not tightly pack together. By keeping the baskets in a flooded state, the solids will remain in a very loose and uniform relation in the baskets, due to the buoyancy of the miscella. This application of excess miscella is continued around the first turn of the exterior and, by maintaining this liquid level in the baskets at all times, we have found that improved extraction and increased capacity are obtained.

Heretofore, when a liquid level was not maintained in the baskets and the baskets were allowed to drain fully, the solids in the baskets

5 packed rather densely and tightly, which not only restricted the full flow capacity through the baskets, but also uncertainly affected the efficiency of the extraction, since only a rather limited quantity of the solvent could drain through the solids in the basket, and flow through the solids was uneven, due to channeling. By keeping the baskets flooded with the miscella during substantially all of their travel from the 10 loading position to close to unloading position, it is possible to pass a maximum amount of solvent through the solids in a given length of travel. This has resulted in an increased thoroughness of extraction and maximum extraction capacity.

15 It will be understood that various changes in the details and arrangements of parts, which have been herein described and illustrated in order to explain the nature of the invention, may be made by those skilled in the art, within the principle 20 and scope of the invention as expressed in the appended claims.

We claim:

1. A horizontal, basket type, solvent extractor comprising a housing, an endless, movable carrier 25 within said housing and having relatively long and straight upper and lower stretches connected by relatively short, semi-circular, ascending and descending end sections, a rotatable support for engaging and supporting each end section and through it supporting said carrier, individually pivoted, open top, perforated bottom, drainage baskets supported by and movable with said carrier in an endless loop path, a charging hopper disposed above the baskets at the start of the 30 upper stretch of their travel, for depositing solids in measured charges into said baskets in succession, an inverting device disposed adjacent its lower stretch near the ascending end section for engaging and inverting said baskets in succession 35 to empty them near the end of the lower stretch of their travel, means carried by said housing and said support and engaging the baskets in their travel from the charging means to the inverting means for keeping them upright, said support for said ascending end section engaging 40 with the inverted baskets and holding them from pivoting on the carrier during their ascent by which they are uprighted, means having a discharge pipe for continuously introducing a solvent-containing liquid into the said basket in 45 charging position and keeping it filled during charging, and circulating means for passing solvent-containing liquid downwardly through said 50 filled baskets in a quantity adequate to keep them also filled with said liquid throughout their path of travel until they reach said inverting means, whereby tight packing of the solids in each basket will be continuously resisted by the buoyancy of the liquid in that basket.

2. In a solvent extraction method of the type 55 in which the solids to be treated for extraction are conducted between loading and unloading positions in baskets with open tops and drainage bottoms, that move in an endless loop path and that pass the solvent-containing extraction liquid 60 through said filled baskets, that improvement which comprises directing into each of said baskets in succession while they are in loading position, a substantial quantity of said solvent-containing extraction liquid, and before such liquid 65 drains off, depositing a charge of the solids to be extracted into the baskets containing such liquid to prevent packing of the solids in the baskets, and during the major part of the travel of 70 the baskets from loading position towards un-

loading position directing more of such extraction liquid into said baskets at a rate sufficiently faster than it can drain off through the bottoms of the baskets to keep the solids from packing by settling in the baskets.

3. In a solvent extraction method of the type in which the solids to be treated for extraction are conducted between loading and unloading positions in baskets with open tops and drainage bottoms, that move in an endless loop path and that pass the solvent-containing extraction liquid through said filled baskets, that improvement which comprises discharging said liquid into the basket in loading position before and during filling of each basket faster than it can drain out, to prevent packing of the solids delivered into the basket in loading position, and delivering solvent-containing liquid continuously into said loaded baskets until they closely approach unloading position, at a rate faster than it can drain out of the baskets so as to keep the solids flooded with the said liquid.

4. In a solvent extraction method of the type in which the solids to be treated for extraction are conducted between loading and unloading positions in baskets with open tops and drainage bottoms, that move in an endless loop path and that pass the solvent-containing extraction liquid through said filled baskets, that improvement which comprises flooding the baskets just before and during their loading with solids with solvent-containing liquid, keeping the loaded baskets flooded with said liquid for the major part of their travel toward unloading position, and during the latter and final part of their travel toward unloading position, flooding the baskets with fresh solvent-containing liquid.

5. In a solvent extraction method of the type in which the solids to be treated for extraction are conducted between loading and unloading positions in baskets with open tops and drainage bottoms, that move in an endless loop path and that pass the solvent-containing extraction liquid through said filled baskets, that improvement which comprises flooding the baskets just before and during their loading with solids with solvent-containing liquid, keeping the loaded baskets flooded with said liquid for the major part of their travel toward unloading position and during the latter and final part of their travel toward unloading position passing fresh solvent-containing liquid through the baskets.

6. A horizontal basket type, solvent extractor comprising a housing, an endless carrier in said housing and having relatively long upper and lower straight stretches and relatively short ascending and descending end portions at the ends of said stretches, a pair of sprocket wheel units, one at each end of the upper stretch and around which the carrier runs in passing from one of said stretches to the other, a plurality of drainage baskets having open tops and apertured bottoms individually and pivotally attached to said carrier in succession and moving therewith, a delivery hopper for delivering measured charges of solids to be treated into said baskets in succession as they start travel with said carrier along said upper stretch, an inverting cam disposed in the path of travel of said baskets adjacent the end of said lower stretch and inverting the passing baskets in succession to empty them, a holder engaging with the inverted baskets and holding them from pivotal movement on the carrier as they move with the ascending portion of the carrier to the starting end of the upper stretch, during

which they are uprighted, spray heads arranged in rows above the baskets as they travel along the upper and lower stretches for delivering solvent liquid into the open tops of said baskets in succession, a plurality of pans arranged in succession beneath the baskets carried by the upper and lower stretches up to said cam, a source of fresh solvent liquid connected to the last of said spray heads beneath which the baskets pass just before engaging with said cam, a pump connected to said pans to remove solvent liquid collecting therein and deliver it to other of said spray heads, so as to circulate the solvent liquid through said baskets repeatedly, and a driving connection to one of said sprocket wheel units for rotating that unit and through it moving said carrier and baskets.

7. A horizontal basket type, solvent extractor comprising a housing, an endless carrier in said housing and having relatively long upper and lower straight stretches and relatively short ascending and descending end portions at the ends of said stretches, a pair of sprocket wheel units, one at each end of the upper stretch and around which the carrier runs in passing from one of said stretches to the other, a plurality of drainage baskets having open tops and apertured bottoms individually and pivotally attached to said carrier in succession and moving therewith, a delivery hopper for delivering measured charges of solids to be treated into said baskets in succession as they start travel with said carrier along said upper stretch, an inverting cam disposed in the path of travel of said baskets adjacent the end of said lower stretch and inverting the passing baskets in succession to empty them, a holder engaging with the inverted baskets and holding them from pivotal movement on the carrier as they move with the ascending portion of the carrier to the starting end of the upper stretch, during which they are uprighted, spray heads arranged in rows above the baskets as they travel along the upper and lower stretches for delivering solvent liquid into the open tops of said baskets in succession, a plurality of pans arranged in succession beneath the baskets carried by the upper and lower stretches up to said cam, a source of fresh solvent liquid connected to the last of said spray heads beneath which the baskets pass just before engaging with said cam, a pump connected to the last pan below the baskets that approach said inverting cam to remove therefrom solvent liquid and deliver it to the spray head above the baskets over the next to the last pan before said inverting cam, other pumps connected to each of the other pans to remove liquid therefrom and deliver it to a spray head, and a driving connection to one of said sprocket wheel units for rotating that unit and through it moving said carrier and baskets.

8. A horizontal, basket type, solvent extractor comprising a housing, an endless, movable carrier within said housing and having relatively long and straight upper and lower stretches connected by relatively short end sections, a plurality of open top, perforated bottom drainage baskets individually pivoted to, supported by and movable with said carrier in an endless loop path, a pair of wheel units, one at each end of the loop, around which the end sections of the carrier pass in changing from one stretch to the other and with the diameter of each wheel unit corresponding to the distance between the stretches of the carrier, a driving connection to one of the wheel units for rotating it and through it mov-

ing said carrier in said path, a hopper device disposed above the basket at the start of the upper stretch, and beneath which the baskets pass in succession from the ascending end of the carrier, for depositing measured charges of solids to be treated into said baskets in succession, a cam disposed along the path of travel of the baskets near the end of their travel in the lower stretch and engaging said baskets in succession and inverting them to empty them, guides along the upper and lower stretches prior to said cam for keeping the baskets from rocking, a holding device movable with the wheel unit at the descending end of the carrier for keeping the baskets upright as they descend from the upper stretch to the lower stretch, a holder moving with said wheel unit at the ascending end of the carrier, engaging with the inverted baskets at the end of the lower stretch and holding them from pivotal movement on the carrier during their ascent to the upper stretch of the loop path, which uprights the baskets during their ascent, pans arranged end to end below the baskets in said upper stretch, and below the lower stretch up to said cam, spray heads disposed above the baskets in their travel with the upper stretch of the carrier and also above the baskets in their travel with the lower stretch of the carrier up to said cam to spray a solvent liquid into said baskets, a pump connected at its intake side with each pan to remove liquid collecting therein, a connection from the delivery side of each pump to one of said spray heads to circulate said solvent liquid over solids in said baskets repeatedly, and a source of fresh solvent liquid connected to the last spray head before the cam.

9. A horizontal, basket type, solvent extractor comprising a housing, an endless, movable carrier within said housing and having relatively long and straight upper and lower stretches connected by relatively short end sections, a plurality of open top, perforated bottom drainage baskets individually pivoted to, supported by and movable with said carrier in an endless loop path, a pair of wheel units, one at each end of the loop, around which the end sections of the carrier pass in changing from one stretch to the other and with the diameter of each wheel unit corresponding to the distance between the stretches of the carrier, a driving connection to one of the wheel units for rotating it and through it moving said carrier in said path, a hopper device disposed above the basket at the start of the upper stretch, and beneath which the baskets pass in succession from the ascending end of the carrier, for depositing measured charges of solids to be treated into said baskets in succession, a cam disposed along the path of travel of the baskets near the end of their travel in the lower stretch and engaging said baskets in succession and inverting them to empty them, a holding device movable with the wheel unit at the descending end of the carrier for keeping the baskets upright as they descend from the upper stretch to the lower stretch, a holder moving with said wheel unit at the ascending end of the carrier, engaging with the inverted baskets at the end of the lower stretch and holding them from pivotal movement on the carrier during their ascent to the upper stretch of the loop path, which uprights the baskets during their ascent, pans arranged end to end below the baskets in said upper stretch, and below the lower stretch up to said cam, spray heads disposed above the baskets in their travel with the upper stretch of the carrier and also above the

5 baskets in their travel with the lower stretch of the carrier up to said cam, to spray a solvent liquid into said baskets, liquid circulating systems with pumps connecting said spray heads and pans for repeatedly circulating a solvent liquid through the charges of solids in said baskets, and a source of fresh solvent liquid connected to the last spray head before the cam.

10. A horizontal, basket type, solvent extractor comprising a housing, an endless, movable carrier within said housing and having relatively long and straight upper and lower stretches connected by relatively short end sections, a plurality of open top, perforated bottom drainage baskets individually pivoted to, supported by and movable with said carrier in an endless loop path, a pair of wheel units, one at each end of the loop, around which the end sections of the carrier pass in changing from one stretch to the other and with the diameter of each wheel unit corresponding to the distance between the stretches of the carrier, a driving connection to one of the wheel units for rotating it and through it moving said carrier in said path, a hopper device disposed above the basket at the start of the upper stretch, and beneath which the baskets pass in succession from the ascending end of the carrier, for depositing measured charges of solids to be treated into said baskets in succession, a cam disposed along the path of travel of the baskets near the end of their travel in the lower stretch and engaging said baskets in succession and inverting them to empty them, a holder moving with said wheel unit at the ascending end of the carrier for engaging with the inverted baskets leaving said cam and holding them against pivotal rocking on said carrier during their ascent to the upper stretch of the carrier, which uprights them, pans arranged below the baskets on the upper and lower stretches of the carrier and arranged in end to end relation in the direction of travel of the baskets, spray heads arranged above the baskets which are above pans, a source of fresh solvent liquid connected to one of said spray heads to deliver fresh solvent liquid thereto, and circulating means connecting the pans and spray heads to move the solvent liquid from pans to spray heads progressively in a selected plan.

11. A horizontal, basket type, solvent extractor comprising a housing, an endless, movable carrier within said housing and having relatively long and straight upper and lower stretches connected by relatively short end sections, a plurality of open top, perforated bottom drainage baskets individually pivoted to, supported by and movable with said carrier in an endless loop path, a pair of wheel units, one at each end of the loop, around which the end sections of the carrier pass in changing from one stretch to the other and with the diameter of each wheel unit corresponding to the distance between the stretches of the carrier, a driving connection to one of the wheel units for rotating it and through it moving said carrier in said path, a hopper device disposed above the basket at the start of the upper stretch, and beneath which the baskets pass in succession from the ascending end of the carrier, for depositing measured charges of solids to be treated into said baskets in succession, a cam disposed along the path of travel of the baskets near the end of their travel in the lower stretch and engaging said baskets in succession and inverting them to empty them, a holder moving with said wheel unit at the ascending end of the carrier for engaging with the inverted

baskets leaving said cam and holding them against pivotal rocking on said carrier during their ascent to the upper stretch of the carrier, which uprights them, pans arranged below the baskets on the upper and lower stretches of the carrier and arranged in end to end relation in the direction of travel of the baskets, spray heads arranged above the baskets which are above pans, a source of fresh solvent liquid connected to the last spray head over the baskets in the lower stretch, and a plurality of pumps, each of one group thereof being connected at its intake side to one of said pans below the baskets in said lower stretch and at its delivery side to said spray head over the next preceding pan below the lower stretch of the carrier, each pump of another group thereof being connected at its intake side of a pan below the upper stretch of the carrier and at its delivery side to the spray head over the pan next along the upper stretch 15 in the direction of travel of the baskets on the upper stretch of the carrier.

12. A horizontal, basket type, solvent extractor comprising a housing, an endless, horizontally elongated carrier within said housing, a rotatable wheel unit at each end of the housing with the carrier passing around said units for support and operation thereby, the carrier stretches between said units being straight, a plurality of open top, perforated bottom drainage baskets individually pivoted to said carrier and arranged in succession along the carrier to move therewith in an endless loop path, a driving connection to one of said wheel units for rotating it and through it moving said carrier to carry said baskets in said loop path, a charging hopper disposed above the baskets at the start of their movement with the upper stretch of the carrier, and discharging solids to be extracted into said baskets in succession, an inverting device disposed at the end of the lower stretch of the carrier, engaging said baskets in succession and inverting them to empty them, a source of fresh solvent liquid, spray heads disposed above and pans disposed below the baskets carried by the upper and lower stretches of the carrier from the charging hopper to the inverting device, and circulating means including pumps and said pans and said spray heads for passing said solvent liquid from said source downwardly and repeatedly through said baskets during their travel from the hopper to said inverting device, according to a selected

5 plan of the order in which the solvent progresses through the succession of baskets.

13. A horizontal, basket type, solvent extractor comprising a housing, an endless carrier, a plurality of open top, apertured bottom baskets attached to said carrier in succession therealong, a pair of wheel units spaced apart horizontally and mounted for rotation about horizontal axes, said carrier running over said wheel units and having relatively long, straight upper and lower stretches between said units, the portions of the carrier running around said units being the ascending and descending end sections connecting said stretches, a driving connection to one of said units for rotating it and through it moving said carrier and baskets, a charging hopper for loading the baskets at the start of the upper stretch, an inverting cam in the path of the baskets at the end of the lower stretch for engaging and inverting the baskets as they pass, spray heads disposed in succession above the baskets in their travel along both upper and lower stretches from the hopper to the cam, pans arranged in succession below the baskets in both upper and lower stretches, and a plurality of circulating circuits including pumps and said heads and pans for creating a rain of solvent liquid from heads to pans along both upper and lower stretches of said carrier through which the baskets move from the hopper to said cam.
